UNITED STATES PATENT OFFICE.

UTLEY WEDGE, OF ARDMORE, PENNSYLVANIA.

FEEDING DEVICE FOR FURNACES.

No. 890,548.

Specification of Letters Patent.

Patented June 9, 1908.

Original application filed October 24, 1906, Serial No. 340,347. Divided and this application filed August 5, 1907.
Serial No. 387,248.

To all whom it may concern:

Be it known that I, UTLEY WEDGE, a citizen of the United States, residing in Ardmore, Pennsylvania, have invented certain 5 Improvements in Feeding Devices for Furnaces, the same being a division of my application, Serial No. 340,347, filed October 24, 1906, and of which the following is a specification.

10 My invention consists of certain improvements in the ore feeding devices for furnaces for which I obtained Letters Patent No. 842,736, dated the twenty-ninth day of January, 1907; the object of my present invention being to so construct such ore feeding devices as to provide for the ready regulation of the feed.

The object I attain in the manner herein-after set forth, reference being had to the 20 accompanying drawing, in which

Figure 1 is a vertical sectional view of sufficient of the upper portion of a roasting furnace to illustrate the construction of the feeding devices therefor in accordance with 25 my invention; Fig. 2 is a view, partly in side elevation and partly in section, on the line *a—a*, Fig. 1, and Fig. 3 is an enlarged view, partly in elevation and partly in section, of one of the elements of the feeding device.

30 In its general structure the furnace may be similar to those in common use, that shown in the drawing having an annular roasting chamber 1 surrounding a central shaft 2, of relatively large diameter, sheathed 35 or incased in blocks 3 of refractory material, the furnace having as many of these roasting chambers 1, located one above another, as the desired capacity of the furnace may suggest, and rotary motion being imparted to 40 the central shaft 2 in any desirable way.

Each of the roasting chambers 1 of the furnace is equipped with a pair of stirrer arms 4, rigidly secured to the central rotating shaft 2, and provided with depending 45 vanes, blades or rabbles 6 for stirring or agitating the material under treatment lying upon the floor or hearth of the furnace chamber.

Above the roof of the furnace is an annular trough 7, which receives the material to be fed to the furnace, this trough having, at any desired points, depending necks 9 which are normally closed at the bottom by means of cone valves 10 but which, when

said valves are open, discharge into the uppermost or primary chamber of the furnace.

Each valve 10 is suspended from a lever 11 suitably mounted in the trough 7, the preponderance of weight on this lever tending to maintain the valve in the closed position, but projecting arms 12 on the upper portion of the shaft 2 have depending lugs 13, which, by contact with the levers 11, depress the same and temporarily open the valves 10.

65 The lugs 13 are preferably pivoted to each arm 12, as shown in Fig. 3, so as to swing in a plane transverse to the direction of movement of the arm, and, when it is not desired to operate the valves 10, said lugs can be turned up through slots 15 in the flange of the arm and adjusted to the position shown by dotted lines in said figure.

Each lug 13, when depending from its carrier arm, acts upon a third arm 16 of the lever 11, and said arm is detachably fitted to a socket on the lever, as shown by dotted lines in Fig. 2, so that it can be removed when it is desired to arrest the operation of the valve 10 corresponding to said lever, 70 two co-acting means being thus provided for regulating the operation of the valves, one governing the individual valves and the other governing the number of times the operative valves will be opened on each rotation of the shaft 2. If, for instance, there are eight valves and the shaft 2 has four arms any number of valves from one to eight may be operated and the valves which are in operation may be operated from one 75 to four times on each rotation of the shaft 2, the feed of material to the furnace being thus accurately regulated to accord with the capacity of the same under varying conditions of working.

95 A chain 17 connects the arm 16 and the lever 11 and prevents loss of the arm when it has been removed from its socket in the lever.

The arms 12 may, as in the feeding device forming the subject of my former patent, carry stirring and feeding blades tending to agitate the mass of material in the trough 7 and feed the same forwardly to the depending necks 9 of the trough, the action of the blades of each arm following so closely the action of the lug 13 upon the lever arm 16 that fresh material will be fed into each

neck 9 during the closing movement of the valve and before the original charge has been exhausted, whereby the valve will be sealed and no material escape of gases through the neck can take place.

5 I claim:—

1. The combination of a furnace with a receptacle above the same having an outlet 10 communicating with the treating chamber of the furnace, a valve closing said outlet, a lever from which said valve is suspended, a movable arm above the receptacle, and a lever-actuating lug mounted upon said arm and movable thereupon into operative or 15 inoperative position.
2. The combination of a furnace with a receptacle above the same having an outlet 20 communicating with the treating chamber of the furnace, a valve closing said outlet, a lever from which said valve is suspended, a movable arm above the receptacle, and a lever-actuating lug pivotally mounted upon said arm.
3. The combination of a furnace with a 25 receptacle above the same having an outlet communicating with the treating chamber of the furnace, a valve closing said outlet, a lever from which said valve is suspended, a movable arm above the receptacle, and a 30 lever-actuating lug pivoted to said arm so as to swing in a plane transverse to the direction of movement of the arm.

4. The combination of a furnace with a receptacle above the same having an outlet 35 communicating with the treating chamber of the furnace, a valve closing said outlet, a valve-carrying lever having a detachable arm, and a movable arm above the lever having a lug acting upon said detachable arm of the latter.

5. The combination of a furnace with a receptacle above the same, a plurality of 40 passages from said receptacle to the furnace, valves for said passages, a plurality of devices for operating said valves, and means 45 whereby the valves and the operating devices therefor may be independently rendered inoperative.

6. The combination of a furnace with a receptacle above the same, a plurality of 50 passages from said receptacle to the furnace, valves for said passages, a plurality of devices for operating said valves, and means whereby each valve and each operating device therefor may be rendered inoperative 55 independently of each of the others.

In testimony whereof, I have signed my name to this specification, in the presence of two subscribing witnesses.

UTLEY WEDGE.
